**HANDLE CONTROLLED SUCTION CLEANER
NOZZLE ADJUSTMENT**

John E. Vance, Canton, Ohio, assignor to The Hoover Company, North Canton, Ohio, a corporation of Ohio

Application March 30, 1955, Serial No. 498,014

15 Claims. (Cl. 15—359)

The instant invention relates to suction cleaners and more particularly to a novel cleaner manipulating means.

It is the prime object of the instant invention to provide a novel manipulating means for a suction cleaner which means is operative to selectively position the suction nozzle of the cleaner.

It is a further object of the instant invention to provide a novel suction cleaner having a manipulating handle and a nozzle body with means interposed between the handle and the body for uniting the handle and the body for raising the nozzle to an inoperative position spaced from the cleaner supporting surface under control of the manipulating handle.

It is also an object of the instant invention to provide a novel suction cleaner having a manipulating handle and a nozzle body with detent and sector control means interposed between the handle and the body for positioning the handle in an upright storage position, in which position the manipulating handle is united with the nozzle body so that rearward movement of the handle to its normal inclined operating position raises the nozzle from the surface on which the cleaner is supported, with the cleaner being maintained in a stable self-supporting condition.

It is another object of the instant invention to provide a novel suction cleaner having a nozzle body which pivotally supports a manipulating handle and motor-fan unit assembly and includes means for uniting the assembly to the nozzle body so that the nozzle body may be tilted rearwardly on the supporting surface by manipulation of the handle to dispose the nozzle in a raised inoperative position. The nozzle body is mounted on a pair of wheels with the pivotal axis of the handle and motor-fan unit assembly located in substantially vertical alignment with the axis of the wheels so that upon raising the nozzle from the supporting surface, the weight of the motor-fan unit and the handle assembly does not oppose the force applied to the handle for lifting the nozzle from the surface.

Still another object of the instant invention is to provide a novel suction cleaner having a nozzle body and a manipulating handle which is operative to tilt the nozzle body rearwardly on the supporting surface to dispose the nozzle in a raised inoperative position, and in which the weights of the various elements of the suction cleaner are so distributed that the cleaner is self balancing when the nozzle is raised as aforementioned, so that the cleaner is stably supported.

Further objects and advantages of the instant invention will appear to those skilled in the art upon consideration of the detailed description of the several preferred embodiments of the invention which follow, reference being had to the drawings in which:

Figure 1 is a sectional view of the novel suction cleaner taken on the line 1—1 in Figure 2 showing the manipulating handle in its upright storage position.

Figure 2 is a sectional view of the novel suction cleaner taken on the line 2—2 in Figure 1.

Figures 3 and 4 are sectional views of the novel suction cleaner similar to Figure 1 and showing the manipulating handle and the nozzle body in alternate positions thereof.

5 Figure 5 is a bottom plan view of the novel suction cleaner of Figure 1.

Figure 6 is a sectional view of a modified form of the suction cleaner constructed in accordance with the instant invention taken on the line 6—6 in Figure 7.

10 Figure 7 is a partial sectional view of the suction cleaner of Figure 6 taken on the line 7—7, and,

Figures 8 and 9 are sectional views of the suction cleaner of Figure 6 and showing the manipulating handle and the nozzle body in alternate positions thereof.

15 Figures 1 to 5 show one form of a suction cleaner constructed in accordance with the instant invention having a nozzle body 10 formed with a nozzle 11 which is normally adapted to be disposed in contiguity to a surface to be cleaned for applying a suction flow of air thereto. A pair of small wheels 12 are mounted immediately behind the nozzle 11 on depending posts 13 which are secured to the nozzle body 10 in any suitable manner. The wheels 12 are adapted to position the nozzle 11 in properly spaced relation to a surface for cleaning operations thereon. A rotary agitator 14 of a known form is rotatably mounted within the nozzle 11 and is driven by a belt 15 entrained over a recessed circumferential portion 16 forming a driven pulley and a driving pulley 17 formed on a projecting end of the motor shaft.

20 The nozzle body 10 continues rearwardly from the nozzle 11 in an enclosing skirt 17 on each side of the body 10. Each of the skirts 17 has a thickened wall portion 18 to which are secured a pair of stud shafts 19, each rotatably mounting a large diameter nozzle body 35 supporting wheel 20. A peripheral furniture guard 21 made of rubber, plastic, or like yieldable material, is secured to the nozzle body 10 on the front and sides thereof. An appearance cover 22 overlies the nozzle body 10 and encloses the operating elements of the cleaner.

25 30 The rear wall of the nozzle 11 is formed with a dirty air stream outlet 23, and a rearwardly directed air duct 24 is secured to the outlet 23 by bolts 25 or the like. The duct 24 terminates in a cylindrical portion 26 which is disposed adjacent to and concentric with the eye of a 35 suction fan 27 which is driven by the motor. The fan 27 is contained within a generally cylindrical housing 28 enclosing the motor-fan unit, which may be of a known form. The housing 28 forms part of the manipulating handle and motor-fan unit assembly and is rotatably mounted within the nozzle body 10 as will appear hereinafter.

35 40 The cylindrical portion 26 of the air duct 24 includes a peripheral flange 29 on the rim thereof formed with a recessed annular bearing 30 in the face thereof. The adjacent wall 31 of the motor-fan unit housing 28 has secured thereto, as by welding, a bearing shoulder 32 which is complementally formed with respect to the annular bearing 30 to seat therein and provide a swivel 45 mounting of the motor-fan unit housing 28 on the nozzle body 10. The aforementioned bearing assembly includes rings 33, 34, of felt or like material, providing an airtight seal at the junction of the air duct 24 and the housing 28.

50 55 The cylindrical portion 26 of the air duct 24 is closed opposite the fan 27 and is formed with a smaller diameter portion 35 terminating in a flat 36 secured to the nozzle body 10 by bolts 37, or the like, to rigidly secure the duct 24 within the nozzle body 10 to support the motor-fan unit housing 28.

60 65 The opposite end of the motor-fan unit housing 28 includes a projecting stud shaft 38 which is seated in a pillow block 39 secured to the nozzle body 10 by bolts 40 or the like. The pillow block 39 includes a liner 41

70 75 The opposite end of the motor-fan unit housing 28 includes a projecting stud shaft 38 which is seated in a pillow block 39 secured to the nozzle body 10 by bolts 40 or the like. The pillow block 39 includes a liner 41

of bearing material such as Oilite for swivelly mounting the housing 28. It is thus seen that the motor-fan unit housing 28 is swivelly mounted within the nozzle body 10 between the opposite sides thereof. The pivotal axis of the motor-fan unit housing 28 is located above the axis of the wheels 20 in substantially vertical alignment therewith for reasons that will appear below. The centerline of the motor-fan unit mounted within the housing 28 coincides with the pivotal axis thereof.

A dirty air discharge conduit 42 is integrally formed with the housing 28 and leads outwardly from the fan chamber. A filter bag 43 of a known form is secured to the discharge conduit 42 in any satisfactory manner known to the art. The motor-fan unit housing 28 additionally includes an integral socket 44 projecting parallel to the dirty air stream discharge conduit 42. A conventional manipulating handle 45 for the cleaner is secured within the socket 44 by any suitable means.

The structure of the novel suction cleaner of this invention, as thus far described, permits the handle 45 to be moved from the upright storage position illustrated to Figure 1 to an angularly disposed position rearwardly of the nozzle body 10, as shown in Figure 4, in which position the manipulating handle 45 may be conveniently grasped by the operator to manipulate the cleaner on a supporting surface which is to be cleaned. The manipulating handle 45, the attached filter bag 43, and the motor-fan unit contained within the housing 28 form a unitary assembly which is swivelly mounted on the axis of the bearings 32, 38, and pivot on that axis in accordance with movements of the manipulating handle 45 relatively to the nozzle body 10. Since the pivotal axis of the motor-fan unit housing 28 is in substantially vertical alignment with the axis of the supporting wheels 20, the weight of the motor-fan unit will be supported on the wheels 20 and will not affect the disposition of the nozzle body 10, which is pivotally mounted on the axis of the wheels 20. Thus, the nozzle body 10 is floatingly supported on the wheels 20 whereby the nozzle 11 may accommodate itself to irregularities in the supporting surface, and it will maintain a fixed disposition relative to surface being cleaned as determined by the wheels 12.

A pair of trail arms 46, 47 extend rearwardly from the nozzle body 10 and are connected at their ends by a laterally extending strut 48. A pair of stabilizing wheels 49 are rotatably secured to the trail arms 46, 47. The trail arm 46 includes an integral, forwardly extending crank arm 50 to which is secured one end of a tension spring 51. The other end of the tension spring 51 is secured to the motor-fan unit housing 28. The trail arm 46 is rotatably mounted on a hub portion 52 formed integrally with the motor-fan unit housing 28, and the trail arm 47 is rotatably mounted in like fashion on the reduced diameter portion 35 of the air duct 24. The trail arms 46, 47 are thus swivelly mounted on the motor-fan unit housing 28 and on the nozzle body 10 for movement in unison relatively to the motor-fan unit housing 28 and the nozzle body 10.

The tension spring 51 operates to bias the assembly comprising the manipulating handle 45 and the motor-fan unit housing 28 in clockwise direction to locate the manipulating handle 45 in the upright storage position as illustrated in Figure 1. The tension spring 51 operates oppositely on the trail arms 46, 47 to bias them in a counterclockwise direction to maintain the wheels 49 in contact with the supporting surface. The counterclockwise movement of the trail arms 46, 47 under the bias of the tension spring 51 is limited by a pair of studs 53 secured to the nozzle body 10 at the rear thereof, and positioned to abut the trail arms 46, 47 as illustrated in Figure 1. In effect, the tension spring 51 will operate to counterbalance at least part of the weight of the manipulating handle 45 and the filter bag 43 when they are dis-

posed in the normally inclined operating position, as illustrated in Figure 4.

There is provided an upstanding lug 54 formed integrally with the motor-fan unit housing 28 and to which a rocker arm 56 is pivotally secured as by a rivet 55. The rocker arm 56 includes a flat end 57 which loosely receives one end of a guide rod 58 secured to the motor-fan unit housing 28 on the land 59. A compression spring 60 surrounds the rod 58 between the land 59 and the flat end 57 of the rocker arm 56. The compression spring 60 is thus operative to bias the rocker arm 56 in a counterclockwise direction about its pivot 55. The opposite end of the rocker arm 56 has secured thereto a roller detent 61.

A bracket 62 is secured to the nozzle body 10 as by rivets 63 or the like. The bracket 62 terminates in a sector portion 64 which cooperates with the roller detent 61. The sector portion 64 includes a first notch 65 for seating the roller detent 61 with the manipulating handle 45 in its upright storage position in the manner illustrated in Figure 1. In the position of the elements as illustrated in Figure 1, the roller detent 61 and the cooperating sector 64 unite the manipulating handle 45 and the nozzle body 10 so that there is no relative movement therebetween. Rearward movement of the manipulating handle 45 to its inclined normal operating position will, accordingly, be transmitted to the nozzle body 10, raising the nozzle 11 from the supporting surface in the manner illustrated in Figure 3. With the nozzle body 10 so positioned, the cleaner will be supported on the wheels 20 and the trailing wheels 49. The cleaner may then be conveniently moved over thresholds and like obstructions for cleaning operations in different rooms. The wheels 20 are of large diameter for further facilitating movement of the cleaner over obstructions.

It is apparent that with the roller detent 61 engaged in the notch 65, the motor-fan unit housing 28 is also united with the nozzle body 10 and fixed with respect thereto. Upon raising the nozzle 11 to its elevated inoperative position in which the nozzle body 10 is tilted rearwardly, the pivotal axis of the housing 28 will move rearwardly in an arc having its center coincident with the axis of the wheels 20. The center of gravity of the motor-fan unit will then be disposed in a vertical plane to the rear of the axis of the wheels 20. Accordingly, the weight of the motor-fan unit, representing the most substantial part of the weight of the cleaner, will not oppose the force applied to the handle 45 tending to tilt the nozzle body 10 rearwardly, but rather will produce a torque operating with the same effect as that force. The torque of the motor-fan unit will, however, be diminished by the counterbalancing effect of the tension spring 51.

The trail arms 46, 47 will at all times be biased by the tension spring 51 in a direction bringing the wheels 49 into contact with the supporting surface, so that there is relative movement of the nozzle body 10 with respect to the trail arms 46, 47 when the body is tilted to its elevated position. Movement of the nozzle body 10 relatively to the trail arms 46, 47 is limited by a stop stud 69 on the body 10, so disposed as to contact the forwardly extending arm 50 on the trail arm 46, as shown in Figure 3. With the cleaner parts disposed as shown in Figure 3, the cleaner will be in a stable condition, supporting itself on the wheels 20, 49, engagement of the arm 50 with the stud 69 preventing the cleaner from falling over rearwardly. A forwardly directed force applied to the manipulating handle 45 will restore the cleaner to its normal position as illustrated in Figure 1 with the nozzle 11 disposed in contiguity to the supporting surface.

When it is desired to initiate or resume cleaning operations with the cleaner, the manipulating handle 45 is moved rearwardly, tilting the nozzle body 10 rearwardly until the stud 69 abuts the arm 50. Further tilting movement of the nozzle body 10 will be impossible without lifting the nozzle body 10 off the floor. Instead, further

rearward movement of the manipulating handle 45 will snap the roller detent 61 over the hump 66 of the sector 64, the force of the compression spring 60 being sufficiently low as to allow this operation of the manipulating handle 45 and release the cleaner body whereby the nozzle drops to the surface being cleaned to the position shown in Figure 4. The roller detent 61 will then be disposed behind the hump 66 of the sector 64 and in front of the hump 67 on the hub portion 46' of the trail arm 46, disposing the handle in a rearwardly inclined position with respect to the surface being cleaned, in which position the manipulating handle 45 is most conveniently available to the user for manipulating the cleaner. The roller detent 61 has a freedom of movement between the humps 66, 67 so that the position of the manipulating handle 45 may vary within the normal operating range thereof in the course of manipulating the cleaner. Should it be desired to use the cleaner of the instant invention under furniture and the like, the manipulating handle may assume a substantially horizontal position. In order to move the manipulating handle 45 to this horizontal position, the roller detent 61 is snapped over the hump 67 to dispose it in the elongated notch 68 formed in the hub portion 46'. To restore the manipulating handle 45 to its upright storage position, it is simply moved upwardly and forwardly, and the roller detent 61 overrides the humps 67 and 66 until it falls within the notch 65.

A second embodiment of the instant invention is illustrated in Figures 6 to 9. The construction of the suction cleaner illustrated in these figures is the same as that of the suction cleaner heretofore described, except as regards the details of the detent and sector control means. Accordingly, the corresponding parts in Figures 1 to 9 bear the same reference numerals distinguished by a prime in the second embodiment shown in Figures 6 to 9. The discussion which follows is limited to the features of the second embodiment which differentiate it from the first embodiment illustrated in Figures 1 to 5.

The motor-fan unit housing 28' includes an integral ear 70 to which is secured a laterally extending detent 71. The cooperating sector 72 is pivotally secured to a lug 73 as by a rivet 74 or the like. A forward extension 75 on the sector 72 has secured thereto one end of a tension spring 76, the other end of which is secured to the nozzle body 10'. The spring 76 is operative to bias the sector 72 in a clockwise direction on its pivot 74. The sector 72 additionally includes a rearwardly extending lever 77 terminating in a flat 78 for pedal operation in opposition to the bias of the spring 76.

The sector 72 includes a first operating notch 79 for maintaining the manipulating handle 45' in its upright storage position. With the handle 45' so positioned, rearward movement thereof will operate to tilt the nozzle body 10' upwardly and rearwardly raising the nozzle 11' from the supporting surface in the manner illustrated in Figure 8. The sector 72 includes a stop stud 80 positioned to abut the trail arm 46' upon rearward movement of the nozzle body 10' to limit the extent of movement thereof. The operation of the control elements in the present embodiment is the same as that described in connection with the first embodiment of the invention, and it will be seen that the axis of the motor-fan unit housing 28' is shifted rearwardly with respect to the vertical plane in which the axis of the wheels 20' is located. The same balanced condition will obtain, as described above, since the center of gravity of the motor-fan unit is coincident with the axis of the housing 28', and the cleaner will sustain itself in a stable self-supporting position.

To put the cleaner into operation, the manipulating handle 45' is restored to its upright position with the nozzle 11' disposed contiguously to the supporting surface. Pressure is then applied to the pedal 78 removing the sector 72 from the detent 71, and the handle 45' is moved rearwardly disposing the detent 71 behind the notch 79.

The sector 72 is then released under control of the tension spring 76, and the detent 71 will be disposed within the elongated notch 81 which provides some freedom of movement of the manipulating handle 45 with respect to the nozzle body 10' within the normal operating range of the handle. Should it be desired to dispose the manipulating handle 45' in a substantially horizontal position for reaching under furniture and the like, the pedal 78 is again depressed, releasing the detent 71 from the elongated notch 81 and disposing it in the elongated notch 82. When it is desired to restore the manipulating handle 45' to its upright storage position, it is simply moved forwardly, whereby the detent 71 will cam the sector 72 rearwardly in opposition to the tension spring 76 until the detent 71 finally snaps into engagement with the notch 79. In all other respects than those above noted, the embodiment of the invention illustrated in Figures 6 to 9 is the same in its construction as the embodiment first described.

The instant invention in manipulating means for suction cleaners has been described in detail herein as embodied in several preferred forms. It will be apparent to those skilled in the art that the described embodiments are subject to modifications falling within the scope of the invention and, accordingly, it is not intended that the scope of the invention be limited except as set forth in the claims which follow.

I claim:

1. A suction cleaner having a nozzle body with a nozzle adapted to be disposed in contiguity to a surface for cleaning thereof, first and second wheel means to support said nozzle body on the surface, means mounting said nozzle body for movement with respect to said second wheel means, a manipulating handle pivotally mounted on the nozzle body, said handle being normally disposed in a rearwardly inclined position for operation of the cleaner and having an alternate upright storage position in which the handle is vertically disposed with respect to the surface, securing means interposed between the handle and the nozzle body for securing the handle in upright storage position fixing the position of the handle relatively to the nozzle body, movement of the handle toward its rearwardly inclined operating position when it is secured in fixed position relatively to the nozzle body tilting the nozzle body rearwardly on the axis of the first wheel means and relative to said second wheel means to dispose the nozzle in an elevated inoperative position, means limiting tilting movement of the nozzle body to locate the body with the weight of the cleaner so distributed as to maintain the cleaner in a stable self-supporting condition, and means operatively upon continued movement of said handle toward its said rearward inclined operating position to release said securing means and allow said nozzle to drop to operating position with respect to the surface.

2. A suction cleaner having a nozzle body with a nozzle adapted to be disposed in contiguity to a surface for cleaning thereof, first and second wheel means to support said nozzle body on the surface, means mounting said second wheel means for movement relative to said body, a motor-fan unit mounted on the nozzle body with the center of gravity thereof disposed in substantially vertical alignment with the axis of the supporting first wheel means, a manipulating handle pivotally mounted on the nozzle body, said handle being normally disposed in a rearwardly inclined position for operation of the cleaner and having an alternate upright storage position in which the handle is vertically disposed with respect to the surface, means interposed between the handle and the nozzle body for securing the handle in upright storage position fixing the position of the handle relatively to the nozzle body, movement of the handle toward its rearwardly inclined operating position when it is secured in fixed position relatively to the nozzle body tilting the nozzle body rearwardly on the axis of the supporting first wheel means

and relatively to said second wheel means to dispose the nozzle in an elevated inoperative position and shifting the center of gravity of the motor-fan unit to a position rearwardly of the axis of the supporting first wheel means, means limiting tilting movement of the nozzle body to locate the body with the weight of the cleaner so distributed as to maintain the cleaner in a stable self-supporting condition, and means operative upon continued movement of said handle toward its said rearward inclined operating position to release said securing means and allow said nozzle to drop to operating position with respect to the surface.

3. A suction cleaner having a nozzle body with a nozzle adapted to be disposed in contiguity to a surface for cleaning thereof, a pair of wheels supporting the nozzle body on the surface, a motor-fan unit for generating a suction flow of air in the nozzle, means pivotally mounting said motor-fan unit on the nozzle body with the center of gravity thereof located above and in substantially vertical alignment with the axis of the supporting wheels, a manipulating handle secured to the motor-fan unit and forming a unitary assembly therewith including a filter bag, said handle being normally disposed in a rearwardly inclined position for operation of the cleaner and having an alternate upright storage position in which the handle is vertically disposed with respect to the surface, means interposed between the motor-fan unit and handle assembly and the nozzle body for securing the handle in upright storage position fixing the position of the handle relatively to the nozzle body, movement of the handle to its rearwardly inclined operating position when it is secured in fixed position relatively to the nozzle body tilting the nozzle body rearwardly on the axis of the supporting wheels and disposing the nozzle in an elevated inoperative position, the center of gravity of the motor-fan unit shifting to a position rearwardly of the axis of the supporting wheels and the weight of the motor-fan unit operating in a direction to tilt the nozzle body rearwardly, means limiting tilting movement of the nozzle body to locate the body with the weight of the cleaner so distributed as to maintain the cleaner in a stable self-supporting condition.

4. A suction cleaner having a nozzle body with a nozzle adapted to be disposed in contiguity to a surface for cleaning thereof, a pair of wheels supporting the nozzle body on the surface, trail arms extending rearwardly from the nozzle body including surface contacting wheels, means mounting said trail arms for movement with respect to said nozzle body, a motor-fan unit for generating a suction flow of air in the nozzle, means mounting the motor-fan unit on the nozzle body with the center of gravity thereof disposed above and in substantially vertical alignment with the axis of the supporting wheels, a manipulating handle pivotally mounted on the nozzle body, said handle being normally disposed in a rearwardly directed position in which the handle is rearwardly inclined with respect to the surface for operation of the cleaner and having an alternate upright storage position in which the handle is vertically disposed with respect to the surface, means for securing the handle in the upright storage position fixing the position of the handle relatively to the nozzle body, movement of the handle to its rearwardly inclined operating position when it is secured in fixed position relatively to the nozzle body tilting the nozzle body rearwardly on the axis of the supporting wheels and relative to said trail arms and surface contacting wheels to dispose the nozzle in an elevated inoperative position and shifting the weight of the motor-fan unit to a position between the axis of the supporting wheels and the axis of the wheels on the trail arms to maintain the cleaner in a stable self-supporting condition, and means operative upon continued movement of said handle toward its said rearward inclined operating position to release said securing means and

allow said nozzle to drop to operating position with respect to the surface.

5. A suction cleaner having a nozzle body with a nozzle adapted to be disposed in contiguity to a surface for cleaning thereof, a pair of wheels supporting the nozzle body on the surface, trail arms extending rearwardly from the nozzle body including surface contacting wheels, a motor-fan unit for generating a suction flow of air in the nozzle, means pivotally mounting the motor-fan unit on the nozzle body with the center of gravity thereof disposed above and in substantially vertical alignment with the axis of the supporting wheels, a manipulating handle secured to the motor-fan unit forming a unitary assembly therewith including a filter bag, said handle being normally disposed in a rearwardly inclined position for operation of the cleaner and having an alternate upright storage position in which the handle is vertically disposed with respect to the surface, means for securing the handle in upright storage position fixing the position of the handle relatively to the nozzle body, movement of the handle to its rearwardly inclined operating position when it is secured in fixed position relatively to the nozzle body tilting the nozzle body rearwardly on the axis of the supporting wheels to dispose the nozzle in an elevated inoperative position and shifting the center of gravity of the motor-fan unit to a position rearwardly of the axis of the supporting wheels, the motor-fan unit being supported between the supporting wheels and the trail arm wheels maintaining the cleaner in a stable self-supporting condition.

6. A suction cleaner having a nozzle body with a nozzle adapted to be disposed in contiguity to a surface for cleaning thereof, first and second wheel means to support said nozzle body on the surface, means mounting said second wheel means for movement relative to said body, a motor-fan unit for generating a suction flow of air in the nozzle, means mounting the motor-fan unit on the nozzle body with the center of gravity thereof disposed above and in substantially vertical alignment with the axis of the supporting first wheel means, a manipulating handle pivotally mounted on the nozzle body, said handle being normally disposed in a rearwardly inclined position for operation of the cleaner and having an alternate upright storage position in which the handle is vertically disposed with respect to the surface, means for securing the handle in the upright storage position fixing the position of the handle relatively to the nozzle body, movement of the handle toward its rearwardly inclined operating position when it is secured in fixed position relatively to the nozzle body tilting the nozzle body rearwardly on the axis of the supporting first wheel means and relatively to said second wheel means to dispose the nozzle in an elevated inoperative position and shifting the center of gravity of the motor-fan unit to a position rearwardly of the axis of the supporting first wheel means, counterbalancing means operative when said motor-fan unit is in said position rearwardly of the axis of said supporting first wheel means to return the motor-fan unit to its position with the center of gravity thereof disposed in substantially vertical alignment with the axis of the supporting first wheel means, the cleaner being maintained in a stable self-supporting condition when the nozzle body is tilted rearwardly, and means operative upon continued movement of said handle toward its said rearward inclined operating position to release said securing means and allow said nozzle to drop to operating position with respect to the surface.

7. A suction cleaner having a nozzle body with a nozzle adapted to be disposed in contiguity to a surface for cleaning thereof, a pair of wheels for supporting the nozzle body on the surface, a motor-fan unit for generating a suction flow of air in the nozzle, means pivotally mounting the motor-fan unit on the nozzle body with the center of gravity thereof disposed in substantially vertical alignment with the axis of the supporting wheels, a manipu-

lating handle secured to the motor-fan unit and forming a unitary assembly therewith including a filter bag, said handle being normally disposed in a rearwardly inclined position for operation of the cleaner and having an alternate upright storage position in which the handle is vertically disposed with respect to the surface, means interposed between the motor-fan unit and handle assembly and the nozzle body for securing the handle in upright storage position fixing the position of the handle relatively to the nozzle body, movement of the handle to its rearwardly inclined operating position when it is secured in fixed position relatively to the nozzle body tilting the nozzle body rearwardly on the axis of the supporting wheels disposing the nozzle in an elevated inoperative position and shifting the center of gravity of the motor-fan unit to a position rearwardly of the axis of the supporting wheels, counterbalancing means operative in a direction to restore the motor-fan unit to its position with the center of gravity thereof disposed in substantially vertical alignment with the axis of the supporting wheels, the cleaner being maintained in a stable self-supporting condition when the nozzle body is tilted rearwardly.

8. A suction cleaner having a nozzle body with a nozzle adapted to be disposed in contiguity to a surface for cleaning thereof, a pair of wheels for supporting the nozzle body on the surface, a trail assembly including arms extending rearwardly from the nozzle body and having surface contacting wheels, a motor-fan unit for generating a suction flow of air in the nozzle, means pivotally mounting the motor-fan unit on the nozzle body with the center of gravity thereof disposed above and in substantially vertical alignment with the axis of the supporting wheels, a manipulating handle secured to the motor-fan unit forming a unitary assembly therewith including a filter bag, said handle being normally disposed in a rearwardly inclined position for operation of the cleaner and having an alternate upright storage position in which the handle is vertically disposed with respect to the surface, means for securing the handle in upright storage position fixing the position of the handle relatively to the nozzle body, movement of the handle to its rearwardly inclined operating position when it is secured in fixed position relatively to the nozzle body tilting the nozzle body rearwardly on the axis of the supporting wheels to dispose the nozzle in an elevated inoperative position and shifting the center of gravity of the motor-fan unit to a position rearwardly of the axis of the supporting wheels, the motor-fan unit being supported between the supporting wheels and the trail arm wheels maintaining the cleaner in a stable self-supporting condition, means on the nozzle body abutting said trail assembly for limiting the tilting movement of the body, and counterbalancing means operative in a direction to restore the motor-fan unit handle assembly to its position in which the center of gravity of the motor-fan unit is disposed in alignment with the axis of the supporting wheels.

9. A suction cleaner as recited in claim 8 in which the counterbalancing means includes a tension spring interposed between said trail assembly and the motor-fan unit, said spring being suspended on a line offset to the front of the axis of the supporting wheels.

10. A suction cleaner as recited in claim 9 in which the point of attachment of the spring to the motor-fan unit is disposed in front of the pivotal axis thereof, the spring counterbalancing the handle when it is disposed in its normal rearwardly inclined position for operation of the cleaner.

11. A suction cleaner as recited in claim 8 including stop means on the nozzle body adapted to abut the trail arms when the nozzle body is disposed in its normal operating position, and said counterbalancing means includ-

ing a tension spring suspended between the motor-fan unit and said trail assembly to maintain the nozzle body and the trail arms in fixed relative disposition with said stop means abutting the trail arms.

5 12. A suction cleaner as recited in claim 8 in which the means securing the handle in upright storage position includes a detent on the motor-fan unit and a sector on the nozzle body, said detent being engageable with the sector to fix the position of the manipulating handle relatively to the nozzle body.

15 13. A suction cleaner as recited in claim 12 including spring means biasing the detent into engagement with the sector, said means on the nozzle body for limiting the tilting movement of the body permitting the detent to be disengaged from the sector by further rearward movement of the manipulating handle.

20 14. A suction cleaner as recited in claim 12 in which the sector is pivotally mounted on the nozzle body and including pedally operated means for releasing the detent from the sector for positioning the nozzle in contiguity to a surface to be cleaned and locating the manipulating handle in its rearwardly inclined normal operating position.

25 15. In a suction cleaner having a nozzle body with a nozzle normally disposed in contiguity to a surface to be cleaned, a pair of supporting wheels rotatably mounted on the nozzle body at the rear thereof, a trail assembly including arms extending rearwardly from the nozzle body and having surface contacting wheels for stabilizing the cleaner, said trail assembly being pivotally mounted with respect to the nozzle body, a motor-fan unit for generating a suction flow of air in the nozzle, said motor-fan unit being pivotally mounted on the nozzle body with the center of gravity thereof disposed above and in substantially vertical alignment with the axis of the supporting wheels, a manipulating handle secured to the motor-fan unit to form a unitary assembly therewith including a filter bag for the reception of dust and like litter, said handle having an upright storage position in which it is vertically disposed with respect to the supporting surface and a rearwardly inclined position for operation of the cleaner, means for securing the handle to the nozzle body in its upright storage position in which the handle is fixed relatively to the nozzle body, said means being releasable for movement of the handle to its normal operating position independently of the nozzle body, movement of the handle to its normal operating position when it is secured to the nozzle body tilting the nozzle body rearwardly on the axis of the supporting wheels and disposing the nozzle in an elevated inoperative position and shifting the center of gravity of the motor-fan unit to a position rearwardly of the axis of the supporting wheels, means on the nozzle body cooperating with the trail assembly for limiting the tilting movement of the nozzle body and maintaining the wheels on the trail arms in contact with the surface, and means interposed between the trail assembly and the motor-fan unit for counterbalancing the motor-fan unit handle assembly, to maintain the cleaner in a stable self-supporting condition when the nozzle body is tilted rearwardly.
